SMOKING PIPE

Wendell Record, Atlanta, Ga.

Application June 27, 1947, Serial No. 757,533

3 Claims. (Cl. 131—216)

1

My invention relates to improvements in smoking pipes.

A primary object of the invention is to provide a pipe of novel construction, wherein the smoke and condensate are caused to pass through an extended channel and into a trap chamber, before entering the stem of the pipe, whereby such smoke is freed, to a great extent, of moisture and nicotine, and a pleasant clean smoke is provided.

A further object of the invention is to provide a smoking pipe of the above mentioned type which may be conveniently cleaned, even while there is burning tobacco in the pipe bowl.

A further object is to provide a pipe of simplified design, and therefore practical and economical to manufacture, said pipe being durable and attractive in appearance.

Other objects and advantages of the invention will be apparent during the course of the following description.

In the accompanying drawings, forming a part of this application, and in which like numerals are employed to designate like parts throughout the same,

Figure 1 is a perspective view of the smoking pipe embodying my invention.

Figure 2 is a perspective view of the pipe bowl removed.

Figure 3 is a perspective view of a coupling member and stem, partly broken away.

Figure 4 is a central vertical longitudinal section through the pipe, with parts broken away.

Figure 5 is a horizontal section taken on line 5—5 of Figure 4.

Figure 6 is a front end elevation of the pipe with the pipe bowl removed, and,

Figure 7 is a fragmentary section taken on line 7—7 of Figure 6.

In the drawings, where for the purpose of illustration, is shown a preferred embodiment of the invention, the numeral 10 designates a pipe bowl of rounded shape having a convex external surface, and provided with the usual tobacco burning chamber 11. The rear side of the bowl 10 has formed in it a vertical dove-tail groove or recess 12, forming a vertical flat surface 12', and extending to the bottom of the bowl. The dove-tail groove 12 is open at its bottom end and has sides 13 which converge upwardly, and the groove 12 terminates short of the top of the bowl forming a stop shoulder 14, having a downwardly inclined wedge surface 15. The bottom of the pipe bowl 10 is provided with a horizontal recess 16, disposed near the rear side of the bowl and lead-

ing into the vertical dove-tail groove 12. The sides 17 of the horizontal recess 16 preferably converge upwardly. It can be seen that the groove 12 and recess 16 constitute a right angle or L-shaped recess in the rear side and bottom of the pipe bowl, Figure 2, and the L-shaped surface formed by this recess is preferably rounded at its corner, as shown at 17'. The forward end 16' of the recess 16 is preferably vertical. Formed in the rear vertical surface 12', near the lower end of such surface and adjacent to the right side 13, Figure 2, is an opening or smoke port 18, leading into the tobacco burning chamber 11 near the bottom of the same, Figure 4. Also formed in the surface 12' near the lower end of the same, and spaced opposite from the port 18, and adjacent to the left side 13, Figure 2, is a preferably substantially hemispherical recess 19, for a purpose to be described.

The numeral 20 designates a coupling member including an elongated stem portion 21, and a substantially vertical combined filter member and head or wedge 22 formed integral with the stem portion and at substantially right angles thereto. The forward end of the vertical member 22 provides a flat surface 23, and the sides 24 of the member 22 converge upwardly. These sides also converge rearwardly, Figure 5, and are adapted to coact with sides 13 of the dove-tail groove 12. The lower end of the vertical member 22 carries a horizontal right angle extension or tongue 25, having a forward vertical end 26 and upwardly converging sides 27, conforming to the sides 17. The top of the member 22 is beveled to provide a downwardly inclined surface 28 for coaction with the surface 15. A fillet 29 is provided where the tongue 25 joins the flat surface 23, and this fillet fits the rounded corner 17' in assembly. Formed in the flat surface 23 of the member 22 is an inverted U-shaped groove 30, preferably semi-circular in transverse cross section. The two legs 31 of this groove 30 are preferably parallel to the sides 24, and their lower ends terminate near and above the tongue 25. The top 32 of the inverted U-shaped groove is disposed near the top 28. The lower end of the right leg 31, in Figure 3, leads into a preferably substantially hemispherical recess 33, formed in the surface 23 at the lower end of such leg. When the coupling member 20 is attached to the pipe bowl 10, as shown in Figure 4, the hemispherical recesses 19 and 33 register and form a substantially spherical filtering or trap chamber, see Figure 5. The lower end of the left leg 31, Figure 3, registers with the port 18 of the bowl

10 in assembly. Near the top of the recess 33 a smoke port 34 is provided, and the port 34 leads from the recess 33 into the main smoke passage 35 of the stem portion 21. The smoke port 34 communicates with the top of the recess 33, as stated, and is inclined downwardly therefrom to connect with the smoke passage 35, see Figure 6. The port 34 is at an angle to the smoke passage 35, with respect to both the vertical and horizontal, see Figures 6 and 7.

The pipe is provided with the usual detachable stem or mouthpiece 36 having a central smoke port 37, in communication with the smoke passage 35.

The use and function of the smoking pipe is as follows:

When the pipe is assembled as shown in Figure 1, it is used in the same manner as any conventional smoking pipe. The combined filter member and wedge 22 with the tongue 25 coat with the L-shaped recess in the pipe bowl, and prevent the leakage of any smoke at that point. There is a wedging action at both sides 24, at the top 28, and at the sides 27 of the tongue 25, and this wedging action effects a good smoke seal. It should be noted that there is no tendency for the pipe bowl 10 to become disconnected from the pipe stem if the user should invert the pipe and tap the open end of the bowl against his hand or another object, as is customary when removing burnt tobacco from the bowl. This tapping action tends to tighten, rather than loosen the wedged connection between the bowl and coupling member 20. However, when it is desirable to take the pipe apart for cleaning the bowl 10 may be readily disconnected from the coupling member without any tapping and without injury to the pipe.

When the pipe is smoked, the smoke is drawn from the bottom of the chamber 11 through the port 18. Such smoke then enters the U-shaped groove 30 and passes completely around the same, and into the spherical trap chamber formed by the recesses 19 and 33. During this travel through the extended passage, a large part of the nicotine in the smoke is filtered from the same, and most of the moisture present is deposited in the U-shaped groove 30 and spherical trap chamber. The remaining clean dry smoke leaves the spherical trap chamber via the smoke port 34, and passes from that port into the main smoke passage 35. An important feature resides in the fact that the angular smoke port 34 communicates with the spherical trap near the top of the same. This prevents the drawing off into the mouth of the smoker any of the fluid which is condensed and collected in the bottom of the spherical trap chamber.

When after continued smoking it is necessary to clean the pipe, it is necessary only to disconnect the pipe bowl from the coupling member 20, at which time the U-shaped groove 30 and hemispherical recesses 19 and 33 may be conveniently wiped out. This cleaning may be done even while there is burning tobacco in the chamber 11.

It is thus seen that the invention provides an extremely simplified construction which is very convenient, and which dispenses with the necessity for separate filter elements in the stem of the pipe. The groove 30 and spherical trap chamber provide efficient means for cooling the smoke and for removing the moisture and nicotine therefrom.

It is to be understood that the form of my invention herewith shown and described is to be

taken as a preferred example of the same, and that various changes in the shape, size, and arrangement of parts may be resorted to, without departing from the spirit of my invention or the scope of the subjoined claims.

Having thus described my invention, what I claim is:

1. A pipe, comprising a bowl having a chamber and an external longitudinal recess extending from the bottom of the bowl to a point adjacent to the top of the bowl so that the recess extends throughout approximately the entire length of the bowl, the recess having its top closed and its bottom open, the recess having undercut longitudinal edges which are disposed inwardly of the outer face of the bowl, said recess having a side face provided adjacent to its bottom with a port leading into the chamber and having a trap recess adjacent to its bottom and spaced laterally from such port, and a coupling member including a stem having a port and an elongated head carried by the stem, said head being adapted for insertion upwardly into said recess and being of substantially the same length as the recess so that the head extends for approximately the entire length of the bowl, said head having longitudinal edges for engagement with the undercut edges, all of said edges being disposed inwardly of the outer face of the bowl, said head having a side face to contact with the side face of the recess, the said face of the head having an inverted U-shaped groove formed therein and including legs which extend for approximately the entire length of the head, the side face of the head having a trap recess adjacent to its bottom and leading into the lower end of one leg, the stem having its port leading into the trap recess of the head, the trap recess of the head being arranged to register with the trap recess of the bowl and the lower end of the other leg being adapted to register with the port of the bowl, the side face of the recess covering the inverted U-shaped groove when the head is held in place within the recess.
2. A pipe, comprising a bowl having a chamber and an external longitudinal recess extending from the bottom of the bowl to a point adjacent to the top of the bowl so that the recess extends throughout approximately the entire length of the bowl, the recess having its top closed and its bottom open, the recess having undercut longitudinal edges which are disposed inwardly of the outer face of the bowl, said recess having a side face provided adjacent to its bottom with a port leading into the chamber and having a trap recess adjacent to its bottom and spaced laterally from the port, a coupling member including a stem having a port and an elongated head carried by the stem, said head being adapted for insertion upwardly into said recess and being of substantially the same length as the recess so that the head extends for approximately the entire length of the bowl, the head having longitudinal edges for engagement with the undercut edges, all of said edges being disposed inwardly of the outer face of the bowl, said head having a side face to contact the side face of the recess, the side face of the head having an inverted U-shaped groove formed therein and including legs which extend for approximately the entire length of the head, the side face of the head having a trap recess adjacent to its bottom and leading into the lower end of one leg, said stem having its port leading into the top of the trap

recess of the head, the trap recess of the head being arranged to register with the trap recess of the bowl and the lower end of the other leg being adapted to register with the port of the bowl, the side face of the recess covering the inverted U-shaped groove when the head is held in place within the recess.

3. A pipe, comprising a bowl having a chamber and an external longitudinal recess extending from the bottom of the bowl to a point adjacent to the top of the bowl so that the recess extends throughout approximately the entire length of the bowl, the recess having its top closed and its bottom open and tapering upwardly longitudinally, the recess having undercut longitudinal edges which are disposed inwardly of the outer face of the bowl, said recess having a side face provided adjacent to its bottom with a port leading into the chamber and having a trap recess adjacent to its bottom and spaced laterally from the port, the bowl having a bottom external recess leading into the external longitudinal recess, and a coupling member including a stem having a port and an elongated head carried by the stem, said head being adapted for insertion upwardly into said longitudinal recess and being of substantially the same length as such recess so that the head extends for approximately the entire length of the bowl, said head having longitudinal edges for engagement with the undercut edges, all of said edges being disposed inwardly of the outer face of the bowl, said head having a side face to contact the side face of the longitudinal

recess, the side face of the head having an inverted U-shaped groove formed therein and including legs which extend for approximately the entire length of the head, the side face of the head having a trap recess adjacent to its bottom and leading into the lower end of one leg, said head having a forwardly extending shoulder to enter the bottom recess of the bowl, said stem having its port leading into the trap recess of the head, the trap recess of the head being arranged to register with the trap recess of the bowl, and the lower end of the other leg registering with the port of the bowl, the side face of the recess covering the inverted U-shaped groove when the head is held in place within the recess.
